UNITED STATES PATENT OFFICE

JOHN JAMES DAHLSTROM, OF NEW ORLEANS, LOUISIANA

CRATE

Application filed June 30, 1931. Serial No. 547,983.

The present invention relates to crates or boxes and particularly to a crate which is of the knock-down type.

An object of the present invention is to provide a knock-down crate which is of relatively light, simple, strong and durable construction and a crate which when folded will occupy but small space, and which when set up will have the bottom, top and various parts thereof interbraced with one another, to provide a relatively strong and rigid structure capable of protecting the contents of the crate.

Another feature of the present invention is to provide an improved corner piece adapted to serve not only as a hinge, but also as a reinforcement between the adjacent walls of the crate and which further may serve as supports for the top, bottom and locking strip employed, and which is so constructed as to admit of the quick and easy knocking down and setting up of the crate.

The invention has for a further object to provide an improved bottom construction of crate which may be quickly and easily set up within the crate and interlocked with the corner pieces and sides of the crate to securely hold the bottom against movement and from pressing inwardly upon the goods which are carried in the crate.

The invention still further aims at the provision of an improved locking strip and means for holding the same in place upon the removable top of the crate, the means embodying features admitting of the quick and easy securing of the locking strip in closed position after the crate is filled and the top adjusted in closed position.

The invention also embodies certain structural features carrying out the above objects and advantages and which readily adapt themselves to use with conventional crate structures so that the present invention maintains substantially the conventional type and shape of crate without sacrifice of the improvements of this invention.

With the foregoing and other objects in view, the invention will be more fully described hereinafter, and will be more particu-

larly pointed out in the claims appended hereto.

In the drawing, wherein like symbols refer to like or corresponding parts throughout the several views,

Figure 1 is a perspective view of a crate constructed according to the present invention, a portion of the locking strip being broken away to show the end structure of the top of the crate.

Figure 2 is a side elevation of the crate.

Figure 3 is a horizontal section taken through the crate substantially on the line indicated at 3—3 in Figure 1.

Figure 4 is a transverse section taken substantially on the line 4—4 and showing fragmentarily the lower portion of the crate with the bottom thereof about to be snapped into position, the dotted lines showing the springing outwardly of the side of the crate during the positioning of the bottom.

Figure 5 is a fragmentary perspective view of the upper end of the crate showing an anchoring and securing attachment for the locking strip, and

Figure 6 is a fragmentary perspective view of the anchoring strip with a modified form of anchoring and holding means therefor associated with the adjacent cleat of the top of the crate.

Referring to the drawing, 10 designates a pair of sides for the crate which may be of any suitable construction and are shown in the present instance as in the form of substantially rectangular open frames with the usual top and bottom strips 11. The crate body also has end walls 12 which are of any suitable construction and may be in the form of continuous boards as shown, and which are also provided at their upper and edge portions with reinforcing strips 13.

Angle plates 14 are nailed or otherwise suitably secured over the longitudinal edges of each side wall 10 by one of its flanges, an angle plate 14 being disposed at each corner of each side 10 and with its other angle portion overlapping the adjacent edge of the adjacent end wall 12. The angle plates 14 are of sufficient width to extend inwardly of the crate and overhang the interior thereof so as

to provide shoulders which face inwardly at each corner of the crate body. Each angle plate 14 is connected by a pivot 15 to the adjacent corner portion of the adjacent end wall 12, the pivot 15 passing through the angle plate and into and preferably through the adjacent strip 13. The pivots 15 may be in the form of nails or the like, and the adjacent upper and lower nails are disposed in substantially axial alignment so that the pivots 15 are used upon which the sides and ends of the crate may be collapsed.

Each angle plate may also be provided with a detent 16 which is punched inwardly with respect to the interior of the crate so as to provide an anchoring stud or projection for engagement with the removable parts of the crate when the parts are in position.

The crate body is provided with a bottom 17 which may comprise crossed longitudinal and transverse strips to provide an open bottom structure for ventilation purposes. The bottom 17 is provided intermediately with a relatively long strip or cleat 18 projecting at opposite ends beyond the lateral edges of the bottom 17 and which, as shown in Figure 4, is adapted to engage beneath the lower edges of the sides 10 of the crate when the bottom 17 is forced downwardly through the crate and snapped past the intermediate portions of the sides 10. This cleat 18 thus holds the bottom against moving upwardly into the interior of the crate should pressure be brought solely upon the bottom. The corners of the bottom 17 rest flat against the inwardly facing shoulders of the angle plates 14 at the bottom of the crate.

The top of the crate is closed by a suitable top or cover 19 which may comprise any suitable structure providing transverse slots 20 which are secured to the top 19 and which project beyond the lateral edges thereof so as to overlap the upper edges of the sides 10 and thus hold the top 19 from falling down into the crate.

One end of the top 19 is provided with a permanent slat or cleat 21 secured to the top, and which extends over the adjacent corners of the top and which engages against the inwardly facing shoulders of the angle plates 14 at the adjacent end of the crate.

The other end of the top 19 is provided with bevelled corners 22 adapted to escape the adjacent angle plates 14 as the top 19 is swung down into position between the upper edge portions of the sides 10. The bevel cornered end of the top 19 is secured in position by means of a lock strip 23 which is of a length corresponding substantially to that of the width of the top and which is slidably disposed thereon for sliding engagement beneath the adjacent angle plates 14 and which is adapted at opposite ends to project beyond the bevelled corners 22 of the top to engage beneath the angle plates 14

and against the detents or projections 16. The locking strip 23 is thus frictionally held against withdrawal from beneath the angle plates except by downwardly and backwardly directed pressure upon the locking strip. 70

As shown in Figure 5, the locking strip 23 may be secured by a nail 24 or the like to the intermediate portion of an anchoring wire 25. The wire 25 is of single length over-turned intermediate its ends which is suitably twisted near its over-turned end to provide a loop 26 which projects beyond the locking strip 23 to engage over upon the adjacent reinforcing strip 13 of the end wall 12 and which may receive a suitable locking device therethrough such as a nail, a bail or the like. 80

The free ends of the anchoring wire 25 extend beneath the adjacent cross slat 20 and are diverged to provide retaining arms 27 which overlap upon the upper side of the top 19 between the longitudinal members thereof. The anchoring wire 25 may thus freely slide back and forth with the locking strip 23 and when the cover or top 19 is removed from the crate, the anchoring wire 25 holds the locking strip in proper relation thereto. 90

The locking wire or member 25 may be slightly modified as shown in Figure 6. In the modification, the locking member comprises a flat strap 28 of metal or the like which is turned over near its intermediate portion to provide a loop for slidable engagement over the adjacent cross slat 20 of the top and which has its free end portions secured against the opposite sides of the locking strip 23 by a rivet 29. The upper leg of the locking member 28 preferably projects beyond the locking strip 23 and has an aperture 30 corresponding to the loop 26 of Figure 5 to receive a suitable retaining device which may be associated with the adjacent end wall 12 for securing the locking strip 23 in closed position. 100

In assembling the crate, it is only necessary to swing the sides 10 and end walls 12 into right angular relation, such as shown in Figure 3, and to then grasp the bottom 17 and place it lengthwise within the body of the crate with one edge of the bottom lowermost. 110

The lower edge of the bottom 17 is first brought into place at the bottom of the crate with the ends of the bottom resting upon the adjacent angle plates 14. The bottom 17 is then forced against the adjacent side 10 of the plate and such action brings the projecting end of the cleat 18 beneath the said side 10. The other edge of the bottom 17 is now forced downwardly with the projecting end of the cleat 18 sliding against the opposite side 10 of the crate, and this downwardly swinging movement of the bottom 17 flexes or bulges the side 10 of the crate outwardly, as shown in dotted lines in Figure 4, so that the end of the cleat 18 may pass down into position. 120

tion beneath the flexed side. The side 10 of the crate now snaps into position over the cleat 18 and thus locks the bottom 17 within the bottom of the crate and in position upon the angle plates 14.

The crate may be provided with any desired horizontal and vertical partitions, separators or any other devices which are required in the packaging of the articles in the crate. The top or cover 19 is now placed on the crate body by first introducing the square end of the top with the slat 21 into one end of the crate beneath the adjacent angle plates 14. The locking strip 23 is moved back into position against the opposite end cross cleat 20 and the bevelled corners of the top 19 are pressed downwardly below the horizontal plane of the adjacent angle plates 14 during which time the locking strip 23 is slid outwardly to project beyond the bevelled corners 22 of the top and to engage beneath the angle plates 14.

The fastening means if used may now be engaged in the loop 26 or, where the strap is employed, in the hole 30 and with the adjacent end wall 12 so as to lock the strip 23 from accidentally sliding out from under the angle plates 14 and releasing the top.

It will be obvious that various changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. A crate comprising a pair of sides, a pair of ends, angle plates secured to the corners of said sides, and projecting inwardly therefrom at the top and bottom of the crate, pivots securing the inwardly projecting portions of the angle plates to the adjacent end walls for pivotally connecting the same to the sides, said angle plates being of sufficient width to project inwardly beyond the sides and ends of the crate and provide inwardly and oppositely facing shoulders at the top and bottom of the crate, a bottom removably fitting in the crate between the sides and ends thereof, a locking cleat carried across the underside of the bottom and projecting beyond the lateral edges thereof for engagement beneath the lower edges of said sides upon the flexing outwardly thereof to lock the bottom against the lower shoulders in the crate, a cover removably fitting in the top of the crate with one end against the adjacent shoulders thereof and having bevelled corners at its opposite ends to escape the shoulders at the opposite end of the crate, a locking slat slidably disposed on the bevelled cornered end of the top and removably engaging beneath the adjacent shoulders of the crate, and

anchoring means disposed between the cover and the locking slat for holding the same to the cover.

2. A crate comprising pivotally connected sides and ends and having inwardly facing shoulders at its upper and lower corners, a bottom removably fitting in the crate between the sides and ends and resting on the lower shoulders, and a cross cleat carried by the bottom intermediate its ends and engaging against the lower edges of the sides for holding the bottom upon the shoulders, said sides being relatively flexible for admitting passage of the ends of the cross cleat therebetween in the removal and positioning of the bottom.

3. In a crate, a reinforcing and pivotally connecting angle plate for use between an adjacent side and end of the crate, comprising a sheet of metal bent intermediately at substantially right angles to provide a pair of flanges, one of said flanges adapted for fixed attachment to the outer face of the side of the crate with the other flange extending inwardly over the adjacent longitudinal edge of the crate near the end of the same and adapted to overlap the exposed edge of an adjacent end of the crate, the said inwardly projecting flange having a detent punched inwardly therefrom to provide a projection for frictional engagement with removable parts of the crate and adapted for pivotal connection with the adjacent end of the crate.

4. In a crate, a body portion, a top for the body portion adapted to fit between the sides and ends thereof, angle plates carried at the corners of the body portion and projecting inwardly from the sides and ends thereof to provide shoulders, said top adapted to engage at one end beneath the shoulder at one end of the body and having bevelled ends adapted to escape the shoulders at the opposite end of the body, a locking strip slidably mounted on said second end of the top for slidable engagement outwardly beneath the adjacent shoulders and beyond the bevelled corners of the top, an anchoring device carried by said locking strip and slidably engaging an adjacent portion of the top, for holding the strip in assembled relation thereto when the top is removed from the crate, said anchoring means having a securing projection extending beyond the locking strip for cooperative engagement with the adjacent end of the crate.
